(57) **CLAIM**

The ornamental design for a gnathostatic model, as shown and described.

DESCRIPTION

FIG. 1 is a front, right perspective view of a gnathostatic model showing our new design;

FIG. 2 is a front elevational view thereof;

FIG. 3 is a rear elevational view thereof;

FIG. 4 is a top plan view thereof, the bottom view being identical thereto;

FIG. 5 is a right side view thereof;

FIG. 6 is a left side view thereof;

FIG. 7 is a front elevational view of the upper jaw side;

FIG. 8 is a rear view thereof;

FIG. 9 is a bottom plan view thereof;

FIG. 10 is a right side view thereof;

FIG. 11 is a left side view thereof;

FIG. 12 is a front elevational view of the lower jaw side;

FIG. 13 is a rear view thereof;

FIG. 14 is a bottom plan view thereof;

FIG. 15 is a right side view thereof;

FIG. 16 is a left side view thereof;

FIG. 17 is a front elevational view showing a state where the upper teeth of the gnathostatic model are removed from the support base;

FIG. 18 is a rear view thereof;

FIG. 19 is a bottom plan view thereof;

FIG. 20 is a right side view thereof;

FIG. 21 is a left side view thereof;

FIG. 22 is a front elevational view showing a state where the lower teeth of the gnathostatic model are removed from the support base;

FIG. 23 is a rear view thereof;

FIG. 24 is a bottom plan view thereof;

FIG. 25 is a right side view thereof; and,

FIG. 26 is a left side view thereof.

The broken line showing of the support base representing the alveolar ridge in FIGS. 1-16 is for the purpose of illustrating environmental structure and forms no part of the claimed design.

The broken lines shown in FIGS. 17-26 represent portions of the gnathostatic model that form no part of the claimed design.
